(57) **CLAIM**

The ornamental design for a multi function display, as shown and described.

DESCRIPTION

FIG. 1 is a front, bottom perspective view of a first embodiment of my design;

FIG. 2 is a front, top perspective view thereof;

FIG. 3 is a bottom plan view thereof;

FIG. 4 is a top plan view thereof;

FIG. 5 is a side elevational view thereof;

FIG. 6 is a side elevational view from the side opposite to that of FIG. 5;

FIG. 7 is a front elevational view thereof;

FIG. 8 is a rear elevational view thereof;

FIG. 9 is a front elevational view of a second embodiment of my design, the remaining views being the same as the first embodiment;

FIG. 10 is a front elevational view of a third embodiment of my design, the remaining views being the same as the first embodiment; and,

FIG. 11 is a front elevational view of a fourth embodiment of my design, the remaining views being the same as the first embodiment.

The dashed lines of the various figures form no portion of the claimed design.
